TYPEWRITING MACHINE

William A. Dobson, Wethersfield, Conn., assignor
to Underwood Elliott Fisher Company, New
York, N. Y., a corporation of Delaware

Application August 4, 1937, Serial No. 157,236

17 Claims. (Cl. 197—22)

This invention relates to light-duty typewriters in the class of standard portable machines, and relates more particularly to the type-actions and to case-shifting mechanism thereof, the latter being effective in shifting the type-bar system or basket.

A general object of the invention is to preserve the features of compactness, so essential in this class of light-duty portable machines, especially with reference to the height of the typewriter. In accordance with the invention the system of type-actions, including key-levers and interconnecting mechanism, affords a close nesting of the parts in a relatively shallow machine, although the parts assume adequate proportions and ample lengths to afford a smooth dependable action during typing and assure free, unencumbered movement of the basket in case-shifting.

A further aim of the invention is to afford an easy finger-touch on the keys, and celerity of operation with minimum inclination or tilting of the keys during the key-strokes. These features have been obtained heretofore, mainly in standard typewriters, by employing key-levers of great length extending back under the type-bar system and pivoted at their rear ends. Key-levers of this sort are embodied in the present invention, but in a light-duty portable machine, without adding to the height of the machine but rather minimizing its height.

Another aim of the invention is to afford operation of the type-bars by the described underlying system of long key-levers, by means of intermediate connections which will permit the up-and-down shifting of the type-bar system while the keys remain stationary and which will enable the described key-levers to operate said type-bars by means of sub-levers of maximum length, thereby to secure ease of action while permitting exceptional compactness of the machine, especially as to height, by mounting said sub-levers forwardly of the type-bar system and reaching up in front of the type-bars and connected to the rear ends of the latter by means of links which are directed downwardly from the sub-lever connection to a point below the adjacent type-heads and then extend rearwardly to connect to the short drive arms of the type-bars.

As described, the key-levers extend under the type-bars and the sub-levers are disposed in up-standing position and are pivoted at their lower ends below the key-levers to extend up between the key-levers, terminating at the upper ends above the level of the types, while the links dip

downwardly from their articulations to the sub-levers and then run back to the type-bars. These upstanding sub-levers with their cam-arms, find ample room in front of the type system at the rear of the key-board and there is ample clearance of the key trains one from another.

The type-bar segment extends downwardly and forwardly from the platen at such angle that types strike at a point a little above the level of the platen axis. The type-bars, at rest, are disposed in a substantially horizontal front and back plane, the arc of the type-bar rest engaging the type-heads, being of lesser curvature than the type-bar-pivot arc, so that the type-bars particularly at the sides of the system, diverge slightly from each other to afford more clearance for the types. The sub-levers are pivoted on a common transverse horizontal fulcrum-rod and are made in gradual lengths so that their terminal ends collectively define an arc, conforming, approximately, with the arc assumed by the type-heads at rest.

The arrangement of the sub-levers in which their free ends are disposed to project in front of the type-bar basket and including type-bar links directed downwardly and rearwardly to collectively define a recess or trough, permits the use of shorter type-bars, thereby minimizing the height of the machine. Such arrangement allows the type-bars to come to rest in a position nearly horizontal and, in view of the backward tilting of the type-bar segment, the type-bars are caused to diverge or spread from each other and, therefore, the type-heads thereon may be closer to the fulcrum point to minimize the length of the type-bar.

The types lie in the type basket which is normally disposed above the curved row of type-bar links and, in case-shifting to the upper type characters, that is, in lowering the type basket, the arrangement permits the forward ends of the typebars to drop back of the upper ends of the sub-levers and into the recess afforded by the L-shaped form of the type-bar links.

In combining said key-levers with said sub-levers, type-bars and links, the links are formed with cam-shaped slots in which pins or wrists on the sides of the key-levers operate. The slots curve downwardly and rearwardly from said pins or wrists, the slots in different sub-levers having different curvatures to compensate for varying effective lengths and strokes of the corresponding type-action parts. These slots are formed in members which extend forwardly from the sub-levers and are so shaped that at the beginning

of the stroke there is considerable motion of the key employed in effecting a short motion of the sub-lever and type-bar so that the start of the type-bar in motion is easy and thus an easy operation is obtained. The lower part of the slot, however, curves backwardly or becomes more abrupt so that at the last part of the key stroke, the type-bar is speeded up and at the same time, the momentum of the operator's hand is gradually absorbed by the type-bar. Thus, the type is cushioned both at the beginning of the stroke and at the conclusion of the stroke.

Other features and advantages will herein-after appear.

15 In the accompanying drawings,

Figure 1 is a perspective view of the typewriting machine embodying the invention, showing the type basket in lowered position for upper case typing, the casing and certain portions of the type-action system being omitted for clarity.

Figure 2 is a fragmentary sectional view taken on a front and back plane at the center of the machine and illustrating typical center and outer type-actions of the system, including the case-shift mechanism, the type-bar basket being shown in raised position for lower-case typing.

Figure 3 is a fragmentary transverse sectional view through the typewriter, taken on the plane just forward of the type-bar segment, to illustrate the means for mounting and guiding the segment for case-shift movement and the case-shifting stops thereof, and

Figure 4 is a view similar to Figure 2 but showing a center type-action only, the type-bar basket being lowered for upper-case typing.

In the preferred embodiment of the invention illustrated, a typewriting machine of the standard portable class is shown, including a framework of vertical side plates 6, a front plate 7, 40 and suitable cross-members such as the transverse bar 8. A system of key-levers 9 is provided, each extending substantially the depth of the machine, being pivoted on a transverse fulcrum-rod 10 at their rear ends and yieldably held 45 in normal position by springs 11, against a stop 12, the key-levers extending through guide-slots in the front plate 7 and carrying keys 13 at their forward ends, the keys being arranged in a series of transverse banks or rows forming a keyboard.

50 Each key-lever 9 has, extending laterally therefrom adjacent the forward end, a wrist or pin 14 engaging in an arcuate slot 15 cut in a forwardly extending member 16 of a sub-lever 17. A series of sub-levers 17 is provided, each one 55 of the series being disposed in upstanding position and fulcrumed on a rod 18 mounted in the transverse bar 8, the latter including a series of guide-slots 19 to guide the respective sub-levers 17 in a vertical plane of travel. To afford adequate length for the various sub-levers 17, particularly those at the center of the machine, the fulcrum 18 of the sub-levers is disposed substantially at or close to the bottom of the machine 60 to extend upwardly therefrom between the key-levers 9 in crossing relation therewith.

The cam-slots 15 are directed downwardly and rearwardly in the sub-levers 17 so that, during depression of a key-lever 9, the pin 14, acting 70 against the lower edge of the slot 15, cams the sub-lever 17 to swing forwardly of the machine on its pivot 18. To compensate for certain differences in the corresponding parts of the various type-actions, such, for example, as the various 75 lengths of key-levers and the different lengths

of sub-levers, to be later particularized, the cam-slots 15 for the respective type-actions vary in angle of inclination and degree of curvature. That is to say, the cam-slots 15 for the outside type-actions, see Figure 2, are inclined less than 5 slots of the central actions since the outer sub-lever, being longer, requires a lesser throw to actuate its type-bar. Further, the degree of curvature for each cam-slot 15 is such that at the beginning of the key-stroke there is a greater 10 leverage to start the type-bar in motion and the cam-slot 15 gradually flattens out to decrease in angularity so that toward the end of the key-stroke, the leverage is so decreased as to absorb the momentum of the operator's hand 15 as the type approaches and strikes the platen.

These differences in the slots 15 have the effect of coordinating the respective type-actions with each other to assure a substantially uniform depth of key-stroke and provide adequate leverage throughout the type-action system. As is well known, a certain type-action may be guided by depression of a key 13 in the rearmost bank, and the adjacent type-action may be operated by a key in the first bank, the mentioned keys differing somewhat in the effective throw of the pin 14 on the cam-slot 15. Similarly, as will be apparent in Figure 2, the center type-actions have a relatively short sub-lever 17 as compared with the sub-lever for the outside type-action 20 shown, the latter being comparatively long. Although the free end of each sub-lever 17 travels an approximately uniform distance during operation, the angular throw of each differs, which difference is accommodated by the mentioned 25 variations in the respective cam-slots 15.

A segment plate 20 is provided for mounting and guiding a system of type-bars 21 in swinging to and from the platen 22 in typing. The type-bars 21 are pivoted on the segment plate 40 20 by an arcuate pivot rod 23 thereon; the type-bars being disposed at their pivoted portions in a series of radial slots cut in the segment 20. The segment 20 has a supporting frame 25 extending laterally from each side thereof by which 45 same is mounted for case-shift movement, to be later particularized.

Arms 26 extend from the frame 25 in support of a curved rest 27 including an arcuate channel bar and a cushion 28 inserted therein against 50 which the type-heads of the type-bars 21 rest in inactive position. The particular arrangement of the type-bar basket, including the segment 20, the type-bars 21, and the rest 27, presents a condition effective in somewhat reducing the 55 height of the machine. The curvature of the pivot rod 23 is of a suitable radius or curvature to guide the type-heads into the striking position on the platen 22 and the curvature of the rest 27 is somewhat flatter or of greater radius than 60 that of the pivot rod 23, so that the respective type-bars 21, particularly those at the sides of the machine, are flared out as in fan formation to diverge from each other thereby affording greater spacing between the respective type-heads thereof. Since each type-head requires a certain clearance, the divergence of the type-bars 21 permits a shorter type-bar, hence reducing the overall height of the machine. The relatively flat curvature of the rest 27 as compared 70 with the curvature of the pivot rod 23, causes the type-bars 21 at the sides of the machine to assume a lower position at rest. The segment plate 20 is tilted at an angle from the vertical, Figure 2, so as to raise the type line on the 75

5 platen to a region of greater visibility to the operator, and more particularly to effect a further flaring of the type-bars 21, in that same are disposed in a substantially horizontal position which thereby affords an arc of travel for the type-bars 21 in an angle greater than the usual ninety degree arc.

10 Each type-bar 21 includes a drive-arm 29 extending rearwardly and downwardly therefrom. 10 Each drive-arm 29 is operably connected to a corresponding sub-lever 17 by a link 30 flexibly joined at 31 to the sub-lever 17 and at 32 to the drive-arm 29.

15 As aforeindicated, the series of sub-levers 17 are of various lengths so that their free ends, articulated to the links 30, define an arc formation, see Figure 1, in circumjacent relation to the type-bar ends in rest position, the sub-lever ends being disposed in front of the type-heads.

20 To accommodate the type-bar basket in either upper or lower case-shift position, the series of links 30 are bowed downwardly so as to define a trough or recess into which the type basket is nested, each link 30 being preferably directed downwardly from the point 31 at the sub-lever 17 and bent to extend rearwardly to the point 32 at the drive-arm 29. The arrangement of the type actions as set forth affords certain economies in manufacture, particularly in that same 25 permits fabrication of substantially uniform dimensions of the links 30. The type-bar basket, as shown in Figure 4, is in lower position in which same is further lowered into the trough or recess formed by the bowed links 30, in which 30 showing, the close nesting of the type action parts will be readily apparent.

35 The arrangement of the sub-levers 17, the links 30, and the type-bars 21 including the drive-arms 29, facilitates case-shift movement of the 40 type-bar basket without affecting the type action, this advantage being had particularly because of the extension of the sub-lever 17 in front of the type-bars 21. The segment 20, in case-shift movement, travels down and up in a 45 plane substantially parallel to its normal face and reciprocates a maximum distance, approximately one-quarter inch. In relation to the parts of the mechanism, as shown in Figure 2, the type-bar basket is in upper position from 50 which it will be noted that the pivot point 32, during case-shift movement to lower position, lowers approximately one-quarter inch. The pivot point 31 is therefore disposed in a plane perpendicular to the plane of travel of segment 55 20 and intersecting the point 32 midway between the two extreme positions thereof. In other words, the point 32 travels during case shifting one-eighth inch either side of a plane normal to the segment 20 and intersecting the point 31, 60 and in view of the adequate length of the link 30, the point 32 moves in a substantially flat arc which digresses only slightly from the path of travel of the segment 20, which digression is allowed by the inherent looseness of the pivot 65 points 31, 32.

70 Although, in the present embodiment of the invention illustrated, the type-bars 21 are shown in approximate horizontal position at rest, and the segment 20 is tilted backward at an angle of about 10 degrees off the vertical, other arrangements of these parts may be employed, it being noted that it is desirable to have an arc of travel for the type-bars 21 somewhat greater than the usual 90 degrees stroke, for example, 100 degrees. 75 As aforeindicated, such an increased

stroke permits the use of shorter type-bars and, therefore, for a given elevation of the platen 22, the pivot of the type-bars may be higher than usual to afford ample clearance between the type-bars and links for downward case-shift movement. These features all result in producing a more compact machine with ample room for the operating mechanisms, the parts of which are of adequate size to assure proper operation, notwithstanding the compactness of the machine. 10

15 The segment 20 is mounted and guided in case-shift movement, preferably as shown in Figures 1 and 3. The segment-supporting frame 25 has its respective ends bent or otherwise formed to provide oppositely-facing raceways 33, including depending portions 34, each raceway having slots 35 formed therein to co-operate with a single ball or roller 36. A complementary raceway 37 for each ball 36 is mounted on the respective side plates 6 of the main frame, the respective raceways 37 including slots 35 for guidingly retaining the ball 36 in case-shift movement.

20 The case shifting of the segment 20 is actuated by the mechanism shown in Figure 2 which includes a case-shift lever 40 fulcrumed at 41 on the side plate 6 and defining a T-shaped formation having a cross member 42 flexibly joined at its upper end to a link 43. The depending portions 34 of the segment frame 25 each have flexibly connected thereto an arm 44 of a bell-crank 45, the latter being pivoted by means of a lateral rock-shaft 46 and including an arm 47 flexibly joined to the other end of the link 43. A case-shift mechanism similar to that described 25 is provided at each side of the machine, the operation of each mechanism being coordinated through the rock-shaft 46 which is journaled in the respective side plates 6 and has fixedly mounted thereon each of the bell-cranks 45. To minimize the effort of the operator required 30 in case shifting, an initially tensioned spring 48 is effective on each of the arms 44 so as to counterbalance the load of the type-bar basket effective on the case-shift mechanism.

35 Means are provided for limiting case-shift movement, embodying case-shift stops illustrated in Figures 1 and 3. Each laterally extending portion of the segment frame 25 has formed thereon a stop lug 50, and a bracket 51 extends from each side plate 6, being formed to present 40 a flange 52 in parallelism with the lug 50. The flange 52 of each case-shift stop carries a pair of stop screws 53 and 54 threadedly engaged therein, each screw including a lock-nut thereon. The screw 53 has its free end depending 45 from the flange 52 to abut the lug 50 so as to determine the upper position of the segment 20. The screw 54 also depends from the flange 52 and extends through an aperture in the lug 50 so as to serve in limiting the downward travel of the 50 segment 20, the screw 54 including a head or collar 55 for engagement with the lug 50 as the segment 20 reaches lower position. Adjustment of the respective screws 53 or 54 determines with accuracy the position of the type-bar basket, 55 particularly the upper and lower type case relative to the printing line on the platen 22.

60 In general, the correlation of the parts of the type-action, as described, and the type-bar assembly or basket, as set forth, produces a number of pertinent features advantageous in the efficient operation of the machine, and at the same time presents a compact organization of mechanism so desirable in machines of the portable light-duty class. The tilting of the seg- 75

ment assures greater visibility of the work and the horizontal arrangement of the type-bars affords a machine of lesser height and facilitates the nesting of the type basket within the trough formed by the recessed or downwardly bent links. Further, gradual lengths of the sub-levers, defining an arc in conformation with the type-heads at rest, permits allocating the points of articulation thereof to the type-bar links in such 10 position with reference to the plane of travel of the segment as to obviate any effect on the type-actions during case-shift movement of the segment, at the same time affording an arrangement which permits the use of substantially uniform links throughout the type-action system.

Variations may be resorted to within the scope of the invention, and portions of the improvements may be used without others.

Having thus described my invention, I claim:

- 20 1. In a typewriting machine having a framework and a platen carried thereon, in combination, a series of type-bars including drive-arms defining a type-bar basket mounted for case-shift movement relative to said platen, means for shifting the type-bar basket in a case-shift movement, a system of key-levers, a series of sub-levers fulcrumed at their lower ends and extending upwardly therefrom across the system of key-levers and in front of the type-bar basket, 25 means operably connecting said key-levers to said sub-levers, and a series of links operably connecting said sub-levers to said type-bar arms and bowed downwardly to form a trough for disposition of said type-bar basket therein.
- 30 2. In a typewriting machine having a framework and a platen carried thereon, in combination, a series of type-bars including drive-arms, resting normally in a substantially horizontal plane and defining a type-bar basket mounted for case-shift movement relative to said platen, means for shifting the type-bar basket in a case-shift movement, a system of key-levers fulcrumed at their rear ends, a series of upstanding sub-levers fulcrumed at their lower ends and extending upwardly therefrom across the system of key-levers and in front of the type-bar basket, means operably connecting said key-levers to said sub-levers, and a series of links operably connecting said sub-levers to said type-bar arms and bowed downwardly to form a trough for disposition of 35 said type-bar basket therein.
- 35 3. A typewriting machine, as set forth in claim 2, in which the sub-levers are of various lengths increasing from the center of the machine and have their free ends defining an outline in conformation with the associated type-bar drive-arm outline to permit uniformity of the connecting links.
- 40 4. A typewriting machine, as set forth in claim 2, in which the link formation defines a trough into which said type-bar basket may recede for upper case-shift movement.
- 45 5. A typewriting machine, as set forth in claim 2, wherein the point of connection of said sub-levers to said links is in front of and adjacent the type-heads of said type-bars.
- 50 6. A typewriting machine, as set forth in claim 1, in which said links are articulated to the free ends of the sub-levers and the points of articulation collectively define a line circumjacent the type-bar free ends.
- 55 7. In a typewriting machine having a framework and a platen carried thereon, in combination, a series of type-bars including drive-arms, resting normally in a substantially horizontal

plane and defining a type-bar basket mounted for case-shift movement relative to said platen, means for shifting the type-bar basket in a case-shift movement, a system of key-levers of the second order fulcrumed at their rear ends adjacent the back of the machine, a series of upstanding sub-levers of the second order fulcrumed at their lower ends near the bottom of the machine and extending upwardly therefrom across the system of key-levers and in front of the type-bar basket, means operably connecting said key-levers to said sub-levers, and a series of links operably connecting said sub-levers to said type-bar arms and bowed downwardly to form a trough for disposition of said type-bar basket therein.

8. In a typewriting machine having a framework and a platen carried thereon, in combination, a type-bar segment mounted on said framework for case-shift movement relative to said platen, a series of type-bars pivoted on said segment to operate in planes radiating from a substantially common center, each of said type-bars normally resting in a substantially horizontal plane, said segment being tilted downwardly and forwardly from said platen so that the respective type-bars diverge relative to each other at rest from the pivots thereof, a system of key-levers extending beneath said type-bars and pivoted at their rear ends, a series of upstanding sub-levers fulcrumed below said key-levers and projecting upwardly through the system of key-levers to terminate in front of and proximal to the free ends of said type-bars, links operably connecting said sub-levers to said type-bars and bowed downwardly to form a trough for admission of said type-bars therein, and means for actuating said sub-levers by movement of said key-levers.

9. A typewriting machine, as set forth in claim 8, in which the sub-lever free ends collectively define a line circumjacent the type-bar free ends.

10. A typewriting machine, as set forth in claim 8, including a type-bar rest engaging the type-heads of said type-bars in inactive position, said links dipping below said rest and extending rearwardly to the articulation with said type-bars.

11. A typewriting machine as set forth in claim 8, in which the key-levers are of the second order and fulcrumed adjacent the back of the machine, and the sub-levers are of the second order and fulcrumed at the bottom of the machine.

12. A typewriting machine as set forth in claim 8, in which the key-levers are of the second order and fulcrumed adjacent the back of the machine, and the sub-levers are of the second order and fulcrumed at the bottom of the machine, the key-levers and sub-levers crossing each other intermediate their ends.

13. A typewriting machine as set forth in claim 8, in which the key-levers are of the second order and fulcrumed adjacent the back of the machine, and the sub-levers are of the second order and fulcrumed at the bottom of the machine, the key-levers and sub-levers crossing each other intermediate their ends, said sub-lever actuating means being effective at the region of intersection of each sub-lever and key-lever.

14. In a typewriting machine having a framework and a platen carried thereon, in combination, a series of type-bars resting normally in a substantially horizontal plane and defining a type-bar basket mounted for case-shift movement relative to said platen and presenting an arcuate formation of the type-heads in a substantially vertical plane, means for shifting the type-bar basket in case-shift movement, a system of key-

levers fulcrumed at their rear ends, a series of upstanding sub-levers of gradual lengths increasing from the center of the machine and fulcrumed at their lower ends, extending upwardly therefrom across the system of key-levers and terminating in front of the type-heads, the terminals of said sub-levers collectively defining an arc circumjacent said type-head formation, a series of links connecting said sub-levers to said type-bars and bowed downwardly to form a trough for admission of said type-bars collectively therein, an arcuate slot in each of said sub-levers, and a pin on each of said key-levers engaging said slot, whereby said sub-lever is swung forwardly to actuate said type-bar during depression of said key-lever.

15. A typewriting machine as set forth in claim 14, in which the arcuate slots in the respective sub-levers incline at decreasing angles beginning from the center of the machine, to compensate for the increasing lengths of the sub-levers.

16. In a typewriting machine having a framework and a platen carried thereon, in combination, a series of type-bars including drive-arms, resting normally in a substantially horizontal plane and defining a type-bar basket, a system of key-levers fulcrumed at their rear ends, a series of upstanding sub-levers fulcrumed at their lower ends and extending upwardly therefrom across

the system of key-levers and terminating in front of the heads of the type-bars, the fulcrums of said sub-levers being on a transverse line forward of the type-bar heads, a series of links articulated to the terminals of said sub-levers and to said type-bar arms, said sub-levers having slots extending upwardly and forwardly of the sub-levers, and pins on said key-levers cooperating with the slots to drive the type-bars, said pins at rest being substantially forward of the terminals of said sub-levers.

17. In a typewriting machine, in combination, a series of type-bars resting normally in a substantially horizontal plane and defining a type-bar basket presenting an arcuate array of the type-heads in a substantially vertical plane, a system of key-levers fulcrumed at their rear ends, a series of upstanding sub-levers of gradual lengths increasing from the center of the machine, fulcrumed at their lower ends and extending upwardly therefrom across the system of key-levers and terminating in front of the type-heads, the terminals of said sub-levers collectively defining an arc circumjacent said type-head array, and a series of links connecting said sub-levers to said type-bars and bowed downwardly to form a trough to admit the type-bars therein.

WILLIAM A. DOBSON.
